UNITED STATES PATENT OFFICE.

PETER PETRI, OF LACON, ILLINOIS.

STARTER.

1,366,097.

Specification of Letters Patent. Patented Jan. 18, 1921.

Application filed September 12, 1917. Serial No. 190,941.

To all whom it may concern:

Be it known that I, PETER PETRI, a citizen of the United States, and a resident of Lacon, in the county of Marshall and State 5 of Illinois, have invented certain new and useful Improvements in Starters, of which the following is a full, clear, and exact description, reference being had to the accompanying drawings, forming part of this 10 specification.

My invention relates more particularly to devices adapted for attachment to internal combustion engines for the purpose of imparting the necessary revolutions to the 15 crank shaft of the engine whereby the engine will be set in motion, the device being equipped with an energy storing element and proper connections from such element to said crank shaft.

One object of my invention is the provision of means whereby the necessary energy 20 may be stored in the device.

Another object of my invention is the provision of suitable connections, adjacent to 25 the crank shaft of the engine, whereby the energy stored in the device may be transmitted to the said crank shaft.

Another object of my invention is the provision of means whereby, when the energy 30 stored in the device is about to be applied to the engine crank shaft, the connections adjacent said crank shaft will be operated automatically.

Other objects of my invention will appear 35 and be described throughout the specification.

The novelty of my invention will be more fully set forth herein and specifically pointed out in the claims.

40 In the accompanying drawings:—

Figure 1, is a front elevation of a typical internal combustion engine showing the application of my device thereto.

Fig. 2 is an enlarged detail, partly broken 45 away and partly in section, showing the connections adjacent the end of the crank shaft for imparting the energy of the device thereto.

Fig. 3, is a side elevation of the device 50 shown in Fig. 1, a small portion of the engine appearing in the lower left hand part of the figure.

Fig. 4 is a plan of parts of what is shown in Fig. 3.

55 Fig. 5 is a longitudinal section of a bearing shown at the right in Figs. 3 and 4.

Fig. 6 shows some of the main portions of the mechanism in perspective.

Fig. 7 is an elevation of parts of the mechanism viewed from the side opposite that 60 shown in Fig. 3, but much enlarged, and

Fig. 8 is a rear elevation of certain parts shown in Fig. 7.

The same reference characters are used to indicate identical parts in all the figures. 65

For purposes of illustration and to show one form in which my invention may be embodied, 1 represents the general structure of an ordinary engine to which a support 2 is attached, the support 2 carrying a bracket 3 in which the shaft 4 is journaled, the latter carrying a sprocket 5 at its forward end and a ratchet 6 between its ends.

The bracket 3 carries a pawl 7 adapted to engage the teeth of the ratchet 6 so that the latter may be turned in one direction, said pawl 7 being held in engagement with said ratchet 6 by a counter-weight 8, the latter serving the double function of the counter-weight and a movement limit. 75

An operating lever 9, shaped as shown more clearly in Fig. 3, is pivotally mounted on the bracket 3 as at 10 and carries a pawl 11 which, when the lever 9 is operated, imparts rotation to the ratchet 6. 80

A coiled spring 12 surrounds the shaft 4 and is attached, at its forward end, to the ratchet 6, its rear end being attached to a bracket 13, the latter being secured to a member 14 which in turn is secured to the 90 engine, the construction and arrangement of parts just described being such that when the lever 9 is operated, the spring 12 will be subjected to tension and the energy required for starting the engine thus stored. 95

The bracket 13 is provided with an aperture through which the rear end 15 of the spring 12 projects as clearly shown in Fig. 3, and the shaft 4 is provided with a collar 17 at its rear end, the collar being secured in 100 place by a pin 18, for example, which passes through it and the shaft 4 and projects at one end from the latter, its path of travel being intercepted by the end 15 of the spring 12, the construction and arrangement of the 105 parts just described being such that the pin 18 by coming in contact with the end 15 of the spring 12 forms a yielding stop for the said end 15 and the shaft 4 and its associated parts, the device being so set that the spring 110 12 is always under some tension, thereby reducing the number of operations required to

be performed on the lever 9 to subject the spring 12 to sufficient tension to operate the device. The aperture 16 increases in diameter toward its outer end as clearly shown in Fig. 5 so that the end of the spring may readily play or flex as the pin 18 meets it in the rotation of the shaft. Thus the blow of the pin will be cushioned as it meets the spring-end.

10 In Fig. 2, I have shown one form of means whereby the energy of the device may be applied to the crank shaft of the engine, the latter being represented at 19 and provided with one member of a dental clutch 20 held 15 in place by a pin 21, or otherwise suitably secured to the crank shaft, (or as shown in Fig. 3, to the usual fan pulley 22 which in turn is secured to the crank shaft) the other member 23 of the dental clutch being loosely 20 mounted on the usual starting member 24 of the starting crank 25, the member 23 of the dental clutch being provided with a sprocket portion 26 over which and the sprocket 5, a chain 27 is trained so that when the dental 25 clutch members 20 and 23 are engaged and the tension of the spring 12 released, the crank shaft 19 of the engine will be rotated.

The jaws of the dental clutch members 20 and 23 are so arranged that they engage 30 one another in one direction only as shown at 28 Fig. 2, to the end that when the speed of the engine becomes greater than the motion imparted to it by the device, the inclined faces of the jaws will cause the disengagement of the member 23 from the member 20 thereby preventing injury to the device.

The clutch member 23 is caused to engage the member 20 by means of an arm 29 which 40 may be pivotally mounted as at 30 in one of the members 31 of the frame of the machine, for example. The arm 29 may be forked as at 32 and engage over the starting shaft 25 so that when the arm 29 is 45 operated the clutch member 23 and the starting member 24 as well as the starting crank 25 will all be moved toward the clutch member 20 which is carried by the crank shaft 19. The endwise movement of the starting 50 crank 25 compresses a spring 33, Figs. 3 and 4, mounted outside of the starting crank support 34, normally serving as a means for holding said starting crank 25 and its associated parts away from the crank shaft 55 19 while the engine is running.

It is to be observed by reference to Fig. 2 that the jaws of the starting member 24 bear such a relation to the jaws of the clutch members 20 and 23 that when the latter are 60 engaged the former do not quite engage the pin 21 to the end that during the operation of the device the starting member 24 cannot interfere with the proper engagement of the jaws of the clutch members 20 and 23.

65 It is to be further observed that should

it be desired to start the engine by means of the starting crank 25, the same can be done without causing the operation of the starting device, the starting crank 25, and its member 24, being simply pushed toward 70 the crank shaft of the engine in the usual manner, the operation being carried out exactly as though my device were not attached.

In Figs. 1 and 3 I have shown a pull 75 rod 35 by means of which the application of the energy of the spring 12 to the crank shaft 19 is accomplished, the pull rod 35 extending forwardly from any suitable foot pedal or other operating device (not shown) 80 to a point below the bracket 3. It is threaded as at 36 and receives an adjustable block 37 to which one end of a spring 38 is attached, the other end being attached to the arm 29. Said spring is of sufficient strength 85 to overcome the tension of the spring 33 and cause the engagement of the clutch members 20 and 23 when the pull rod 35 is operated.

A second adjustable block 39 is mounted 90 on the rod 35 and is attached to the lower end of a bell crank 40, the latter being mounted as at 41 on the bracket 3 and having its short arm in engagement with a portion of the pawl 7 so that when the pull 95 rod 35 is operated the pawl 7 is raised out of engagement with the ratchet 6.

A second bell crank 42 is suitably mounted on the bracket 3 and shaped as more clearly shown in Fig. 4, its long arm occupying a position in the line of travel of the bell crank 40. Its short arm is adapted to bear against the pawl 11 to hold it in such a position that the ratchet 6 may turn freely, the construction and arrangement 105 of the parts just described being such that the pawls 7 and 11 will only be disengaged from the ratchet 6 when the pull rod 35 is operated to cause the engagement of the clutch members 20 and 23.

The pawl is forked at its upper end as shown more clearly at 43 to engage the sides of the ratchet 6 so that it is always maintained in proper position with relation thereto. The lower end of the pawl is pivotally connected to the lever 9, and in order to exert pressure on the pawl 11 to cause it to engage the ratchet 6, the pivot member connecting the pawl 11 and lever 9 may be extended as shown at 44 Fig. 4 and a spring 110 45 may be attached at one end thereto. The upper end of said spring is attached to the member 2. Said spring serves both as a means for causing the engagement of the pawl 11 with the ratchet 6 and as a means 115 for returning the lever 9 to a position shown in Fig. 3 after it has been operated to subject the spring 12 to tension.

The upper end of the lever 9 may be forked as shown by dotted lines 46 Fig. 1 130

and a sheave 47 may be mounted therein to afford means whereby the energy necessary to subject the spring 12 to the proper tension may be reduced, this reduction being 5 accomplished by securing one end of a cable or other flexible medium to some stationary part of the machine, the cable then passing over the sheave 47 and to a suitable location for operation which, when the device is used 10 in connection with an automobile, is usually a point easily reached by the driver of the vehicle, the movement of the free end of the cable 48 being twice as great as the travel of the lever 9, the consequent required 15 energy is one half.

In cases where the compounding above mentioned and described is not required, a suitable rod or cable 49, dotted lines, Fig. 3 may be attached directly to the lever 9 20 for its operation.

The operation of the device is as follows:

When it is desired to start the engine the lever 9 is operated a sufficient number of times to subject the spring 12 to the required tension, the shaft 4 being turned, in 25 obtaining such tension, through nearly a full revolution, the pin 18 being carried from one side of the spring-end to the other, whereupon the operator depresses the foot 30 pedal or otherwise causes a movement of the pull rod 35. The latter through the connections previously described, causes the engagement of the clutch member 23 with the member 20, and operates the bell crank 40 to 35 raise the pawl 7 out of its engagement with the ratchet 6, the movement of said bell crank 40 also operating the bell crank 42 to simultaneously disengage the pawl 11 from the ratchet 6, releasing the spring 12. The 40 energy of the latter through the chain 27 is transmitted to the crank shaft 19, thereby setting the latter in motion, starting the engine.

As shown in Fig. 3 a coil spring 50 may 45 connect the bell crank 42 with the bell crank 40 to prevent rattle and to insure the return movement of the bell crank 42 after the pull rod 35 has been operated.

As a means of maintaining the proper tension of the chain 27, an adjusting screw 51, 50 Figs. 3 and 4, may pass through lug 52 on bracket 3 and bear against the support 2, and the bracket 3 may be provided with a slotted hole as at 53 Fig. 1 so that said 55 bracket 3 may be adjusted to raise or lower the shaft 4.

By means of the adjustments provided for the blocks 37 and 39 on the pull rod 35 the tension of the spring 38 may be varied and 60 the position of the bell crank 40 may be changed so that the separate parts of the device may be caused to properly function.

To assist in maintaining the proper alignment of the parts of the device, and as 65 clearly shown in Fig. 4, a tube 54 is mount-

ed in the rear bracket 13 and surrounds the shaft 4, extending from the rear bracket 13 to a point adjacent the hub of the ratchet 6. This tube serves a double function of maintaining alinement of the rear bracket 13 and 70 preventing distortion of the spring 12 when the latter is fully wound.

Having thus fully described my invention, I claim:

1. In a starter the combination of a 75 bracket adapted to be mounted on an engine, a shaft carried by said bracket, a spring surrounding a portion of said shaft, a rear support to which said spring is attached, a ratchet carried by said shaft to which said 80 spring is attached, a pawl for operating said ratchet to subject said spring to tension, a lever for operating said pawl, a second pawl carried by said bracket and engaging said ratchet, means for disengaging said pawl to 85 release said spring, and connections between said shaft and a movable part of the engine whereby when said spring is released the movable part of the engine is set in motion.

2. In a starter, in combination with a 90 gearing for rotating an engine crank-shaft, of a power delivering mechanism including a support and a shaft, a ratchet wheel secured to the latter, a spring surrounding the shaft, fixed at one end with respect to the 95 ratchet wheel, and at its other end relatively to the support, and having a free extremity capable of lateral flexing movement, and a stop on the shaft in position to engage the said free extremity in the rotation of said 100 shaft.

3. In an engine starter the combination of a support, a shaft carried at one end therein, a coil spring surrounding a portion of said shaft, a support for the opposite end of the 105 shaft to which said spring is attached, said spring at one end being fixed relatively to the shaft, said spring at its end attached to the support having a free portion adapted to flex, and a laterally extending part on the 110 shaft adapted to engage said free portion.

4. In a starter the combination of a shaft, a forward bearing for said shaft, a rear bearing for said shaft, a housing extending from said rear bearing toward said forward 115 bearing and surrounding said shaft, a spring surrounding said housing and attached to said rear bearing and to a winding member, a winding member secured to said shaft whereby said spring is subjected to tension, 120 and connections from said shaft whereby an engine may be started.

5. In a starter the combination of a crank shaft clutch, a sprocket carried thereby, an arm adapted to engage said clutch to shift 125 the latter longitudinally into engagement with the crank shaft of the engine, a shaft, a sprocket on said shaft, a chain connecting said sprocket and the sprocket of said clutch, a ratchet carried by said shaft, a spring se- 130

- cured to said ratchet and to a stationary member, an operating lever, a pawl carried by said lever for engaging said ratchet whereby said spring may be subjected to 5 tension, a second pawl for maintaining the tension to which said spring is subjected, an arm for disengaging said second pawl from said ratchet, an arm for disengaging the first mentioned pawl from said ratchet, said 10 arm being operated by said second mentioned arm, a pull rod for operating said second mentioned arm, and a yielding connection between said pull rod and said first mentioned arm whereby when said pull rod is 15 operated said clutch will be caused to engage the crank shaft of the engine and said pawls will be caused to disengage said ratchet and the energy of said spring will be transmitted to the crank shaft of the engine.
- 20 6. In an engine starter, the combination with a clutch portion for engaging the engine shaft, of a power delivery element, a spring connected therewith adapted to be placed under tension to drive the same, a 25 spring-winding pawl to engage the element, and a stop-motion pawl also to engage said element, a driving connection between the element and the clutch portion, a lever mechanism for disengaging both pawls from the

element including a part to engage the 30 clutch portion with the engine shaft, and an elastic member connecting the said part and the said lever mechanism.

7. In a starter attachment for an internal combustion engine, the combination with the 35 engine shaft and a movable clutch portion for engaging the same, of a bracket adapted for attachment to the engine, a shaft supported therein, a ratchet wheel secured upon the shaft, a spring surrounding the shaft attached at one end to the ratchet wheel and fixed at its other end, a sprocket wheel on said shaft, a driving connection between the sprocket wheel and the said movable clutch portion, a lever mounted on the support, a 40 pawl carried thereby adapted for winding the spring through said ratchet wheel, a stop-motion pawl mounted on the support 45 engaging the ratchet wheel, lever-mechanism for simultaneously disengaging both 50 pawls from the ratchet wheel including a part for manually operating said lever, a lever engaging the said movable clutch portion, and an elastic member connecting the last named lever and the manually operated 55 part.

PETER PETRI.
